VENTILATOR

Arthur L. Lee, Upper Arlington, Ohio, assignor
by mesne assignments, to The Jeffrey Manufacturing Company, a corporation of Ohio

Application December 12, 1945, Serial No. 634,443

9 Claims. (Cl. 230—207)

1

My invention relates to ventilators and more particularly, but not necessarily, to ventilators adapted for use in ventilating underground mines.

In large mines ventilators are generally placed above ground and connected to vent passageways of the mines for constantly changing the air therein. It is pertinent in mining that the ventilators be kept in continuous operation. In the past, in order to lubricate the fan arbor or spindle of such ventilators, it has been necessary for a maintenance man to enter the ventilator housing while the ventilator was in operation. To this end it has been customary to associate an air lock with the ventilator housing to permit a person to enter the housing while the ventilator is in operation. Accordingly, in order to obviate the necessity of a person's entrance into the ventilator and thereby the necessity of the air locks it is an object of my invention to provide an improved ventilator or fan spindle contained within the spindle housing having a closed lubricating system including a sump adapted to contain a quantity of lubricant from which the arbor or spindle bearings are lubricated and to provide means positioned outside of the ventilator housing for determining the quantity of lubricant in the sump and for introducing lubricant thereinto while the ventilator is in operation.

It is another object of my invention to provide in an arbor or spindle an improved lubrication system wherein lubricant is caused to be raised from a sump and to flow by reason of gravity into and through the arbor or spindle bearings while the arbor or spindle is in operation.

Still another object of the invention is to provide in an arbor or spindle wherein the spindle shaft is supported in separately enclosed bearings an improved lubrication system wherein lubricant is raised from a sump and distributed through passageways to each of the bearing enclosures and returned therefrom to the sump.

Other objects of the invention will appear hereinafter, the novel features and combinations being set forth in the appended claims.

In the accompanying drawings,

Fig. 1 is a diagrammatic plan view of a ventilator embodying one form of my invention;

Fig. 2 is a fragmentary sectional view of a portion of the ventilator seen in Fig. 1, the view being taken in a horizontal plane intersecting the arbor or spindle axis of the ventilator;

Fig. 3 is a view in section, the section being taken on line 3—3 of Fig. 2;

2

Fig. 4 is a sectional view drawn to a larger scale, the view being taken on line 4—4 of Fig. 2;

Fig. 5 is a view of the arbor housing end cover plates shown in Figs. 2, 3, and 4;

Fig. 6 is a view of a preferred form of mechanism by which the level of the lubricant within the arbor or spindle housing is determined from outside the ventilator housing and by which lubricant is introduced thereinto while the ventilator is in operation;

Fig. 7 is a diagrammatic fragmentary view in plan of a ventilator embodying another form of my invention;

Fig. 8 is a fragmentary elevational sectional view of the fan arbor or spindle used in the embodiment of the invention shown in Fig. 7, the section being taken in a vertical plane intersecting the arbor or spindle axis; and

Fig. 9 is a view in section of a drive shaft and its housing, the view being taken on line 9—9 of Fig. 2.

Referring particularly to Fig. 1 of the drawings, the ventilator shown therein includes a casing or housing 10 that is comprised of a portion 11 of rectangular cross-section that may be connected to a vent shaft of an underground mine and a portion 12 of circular cross-section that are joined at 13. Mounted within the portion 12 of the ventilator housing 10 and extending into the portion 11 is a fan or blower mechanism 14, the arbor or spindle of which is encased in a multi-pieced streamlined fairing 15 which is faired with the hub of a fan or air impeller rotor having blades 16. Positioned to one side of the ventilator housing 10 is a motor shed 17 that houses the driving motor 18 of the ventilator. Extending between the motor shed 17 and into the fairing 15 is a drive shaft casing 19. The drive mechanism for the fan or air impeller includes the motor 18 which is connected through a connector 20 to a drive shaft 21 that includes a pair of self-centering universal joints 22 to an arbor or spindle mechanism 25 contained within the fairing 15.

Positioned within the motor shed 17 and connected with the arbor or spindle mechanism 25 by conduits is an apparatus 23 for determining the level of the lubricant in the arbor or spindle housing and for introducing lubricant thereinto from outside the ventilator housing while the ventilator is in operation. The ventilator shown is arranged so that the fan or impeller will be driven to withdraw air from the mine vent through the rectangular portion of the ventilator housing 10.

Referring to Fig. 2, a portion of the ventilator seen in Fig. 1 is shown in section, said portion including parts of the rectangular and circular portions 11 and 12 of the housing 10, a portion of the fan shed 17, the arbor or spindle mechanism 25, and the rotor 34 including blades 16. It is to be understood that the construction shown is more or less diagrammatic because the ventilator is drawn to a greatly reduced scale. The arbor or spindle mechanism 25 is mounted centrally in the housing by a pair of struts 24 and a pair of supports 26 that are of streamline cross-sectional contour and these supports extend through the inwardly tapering conical section or throat 27 of the circular portion 12 of the ventilator housing and are secured to the concrete base or foundation 28 of the ventilator.

The arbor or spindle mechanism 25 supports the rotor 34 at its left end. A streamlined member or tailpiece 29 of the fairing 15 is mounted to the left of the rotor 34 and centrally within the circular portion 12 of the ventilator housing 10 by a plurality of radially extending vanes 30 that function to straighten the flow of air as it passes through the housing and to increase the efficiency of the fan or air impeller. The arbor or spindle 25 is housed in a streamline member of nose piece 31 of the fairing 15; one purpose of the fairing 15 being to improve the air flow characteristics of the ventilator.

The drive shaft casing 19 extends through an opening 32 of a wall 33 of the motor shed and the conical throat section 27 into the streamlined nose piece 31 of the fairing 15 to complete the fairing structure for the arbor mechanism 25 and that portion of the drive shaft 21 that is within the ventilator housing. Preferably a fairing structure 35 (see Figs. 2 and 9) is positioned within the circular section 12 to the left of the drive shaft casing 19 and is secured to the nose piece 31 and the wall of the circular portion of the housing 10 to provide for correct air flow about the drive shaft casing.

The construction of the ventilator housing is such that the drive shaft casing 19 may be removed from the ventilator by detaching its fastening plate 36 from the wall 33 of the motor shed and by drawing the casing 19 into the motor shed to permit the drive shaft 21 to be disconnected from the arbor or spindle 25 for permitting the removal of the arbor or spindle 25 from the housing 10 should it ever become necessary to repair it. Preferably the drive shaft housing 19, struts 24, and the arbor supports 28 are sealed to the throat section 27 of the ventilator housing where they pass through it.

The arbor or spindle mechanism shown in Fig. 2 is drawn to a larger scale in Fig. 4. In this particular embodiment of my invention the mechanism of the arbor or spindle is contained within a shell-like housing or casing 38 that is of ogival external contour. The housing or casing 38 may be and preferably is a casting that provides in its nose a bore 39 that receives a bearing assembly 40 that includes a pair of open type anti-friction bearings 41 which are spaced apart by a spacer sleeve 42. The inner end of the bore 39 provides a shoulder 43 against which the inner bearing 41 abuts. An arbor or spindle shaft 44 extends through and is supported by the bearings 41. The arbor or spindle shaft 44 is splined at 45 for receiving a gear 46 that includes a hub 47. Hub 47 abuts the inner race of the inner bearing 41. The forwardly extend-

ing end of shaft 44 carries a spacer sleeve 48 against which an end bearing 49, also of the open anti-friction type, is clamped by a suitable lock mechanism including a nut 51 and lock washer 52.

The opposite end of the shaft 44 carries the rotor 34 and is locked or clamped to the bearing assembly 40 by a pair of nuts 53. Thus the shaft 44, bearing assembly 40, gear 46, spacer sleeve 48, end bearing 49, nut 51 and lock washer 52 become a rigid assembly. A cap 54 fits the nose of the housing 38 and is provided with an inwardly extending shoulder or lip 55 that bears against and clamps the bearing assembly 40 within the bore 39 and against the shoulder 43 when screws 56 are tightened. A suitable gasket 57 is provided for sealing the cap 54 to the housing 38. The left-hand end of shaft 44, as viewed in the drawings, extends through a central opening in cap 54 and carries the rotor 34, the rotor being keyed and removably attached to the shaft. The cap 54 includes a packing 58 that forms a lubricant seal between the housing or casing 38 and the shaft. The opposite end of the housing 38 is closed by a disc-like plate 60 that includes a central bore 61 for receiving the end bearing 49. A cap 62 covers the outer end of the bore 61 in the plate 60 and is sealed by a gasket 63 against which it is clamped by screws 64.

From the description thus far given, it will be seen that the bearing assembly 40 only is secured against endwise movement in the arbor or spindle housing 38, the end bearing 49 being free to slide within the bore 61 of the end plate 60. Thus expansion and contraction of the arbor or spindle housing and shaft may occur without damaging any of the arbor members. Furthermore, bearing assembly 40 takes the axial thrust on shaft 44 produced by rotor 34 when rotating. The entire support for rotor 34 and drive shaft 44 is through the bearings 40 and 49 housed by and carried at opposite ends of the housing 38.

Extending outwardly from the arbor housing 38 is a hollow boss 66 that is adapted to receive a pinion shaft 67 and its supporting anti-friction bearings. The pinion shaft 67 and its supporting bearings are secured in the bore of the boss 66 in a manner identical to that described in connection with the bearing assembly 40.

The arbor or spindle mechanism 25 includes a sealed self-contained lubricating system. That is, the arbor or spindle housing 38 forms a sump 55 adapted to contain lubricant into which the gear 46 extends and from which lubricant is continuously circulated to the arbor or spindle bearings during operation of the arbor. Positioned in the top of the arbor or spindle housing 38 is a pair of troughs or chutes 69 and 70 that function to catch lubricant slung or thrown from the sump by the gear 46 and to cause the lubricant thus caught to flow by gravity into wells or receivers 71 and 72. The well or receiver 71 is formed in the arbor or spindle housing 38, and the well or receiver 72 is formed in the plate 60.

Referring particularly to the arrangement of the well or receiver 71 in the housing 38 and to the bearing assembly 40, the spacer sleeve 42 is grooved circumferentially in its outer surface, as seen at 73, and bored radially at 74 through the groove to provide lubricant passages therethrough. An opening, passage, or conduit 75 in the bottom or floor of the lubricant well or receiver 71 aligns with the peripheral groove 73

in the spacer sleeve 42. Lubricant flows downwardly from the well 71 through the opening 75, the groove 73, and bores 74 into a pocket or recess 76 formed by the sleeve 42 that functions to distribute and direct lubricant into the open bearings 41 from where the lubricant flows back into the sump.

The trough or chute 70 conveys the lubricant which it catches and spills into the lubricant well or receiver 72 in the plate 60. The cap 62 is bulged outwardly to enclose completely the end of the arbor shaft 44 and to provide a lubricant pocket or distributor 77 which directs lubricant into the end bearing 49. Lubricant, after passing through the bearing 49, flows back into the sump. The well or receiver 72 and pocket or distributor 77 are connected by an opening, conduit, or passage 78 that directs lubricant from the well 72 into the pocket or distributor 77.

In operation, the gear 46 is driven by a pinion gear 79 on the pinion shaft 67 and the teeth of the gear, as well as its other surfaces, splash or sling lubricant from the sump upwardly where it is caught by the troughs 70 and conveyed to each end of the arbor housing 38 where it is spelled into the receivers 71 and 72. The depth to which the housing 38 is filled with lubricant is preferably below the bottoms of the bearings 41 and 49. The preferred level is indicated by a line 80. That portion of the housing 38 which forms the sump is below this line. From the wells or receivers 71 and 72 lubricant flows by reason of gravity into the pocket or distributor 77 and is directed thereby into the open type anti-friction bearings from which it flows back to the sump to be recirculated.

The arbor or spindle housing 38 is provided above the trough or chute 70 with a boss that is drilled and tapped at 82 to provide a connection to which a vent or a pressure balancing conduit 85 (see Fig. 3) is connected. The bottom of the arbor housing also includes a boss that is drilled and tapped at 83 to provide for the connection of a lubricant supply conduit 86 thereto.

Referring now to Fig. 3, the portion 23 of the lubricating system connected to the arbor or spindle housing 25 is shown. The apparatus 23 is positioned outside of the ventilator housing and within the motor shed 17. By this mechanism the level of the lubricant within the sump is readily determined and lubricant may be introduced into the arbor or spindle housing or sump while the ventilator is in operation. When ventilators are in operation, the pressure within the ventilator housing is either above or below the pressure on the outside thereof, depending upon whether the ventilator is functioning to force fresh air into the mine or to withdraw air from it. Were the housing 38 to be opened directly to outside pressure, the differential between the pressures would tend to withdraw lubricant through the lubricating seal into the ventilator housing or in the case of a positive pressure to displace lubricant outwardly through the filler opening. Accordingly, features of my invention reside in the mechanism 23 that is associated with the housing 38 for determining the lubricant level in and for introducing lubricant thereto while the ventilator is in operation.

The mechanism 23 that I employ includes the vent or pressure equalizing conduit 85 connected to the vent opening 82 in the top of the arbor or spindle housing 38. The lubricant supply conduit is connected to the supply opening 83 in the

bottom of the arbor or spindle housing and extends outwardly through the fairing 15 and into the motor shed 17. Connected between the vent conduit 85 and the supply conduit 86 within the motor shed 17 is a liquid level indicator in the form of a sight tube 87 for indicating the level of the lubricant within the sump of housing 38. Connected through the medium of a valve 88 and a valve 89, which will hereinafter be called a vent valve and supply valve, respectively, is a container or reservoir 90 that contains fresh lubricant which may be added to the sump through the supply conduit 86.

Referring particularly to Fig. 6, the reservoir 90 is connected at its bottom through pipes 91 and 92 to the supply valve 89 and the top of the tank 90 is connected through a pipe 93 to the vent valve 88. The top of the reservoir 90 is provided with a closure member 94 in the form of a removable air tight cap that may be removed to replenish lubricant therein. The pipes described include suitable connector fittings, and connected between the pipes 93 and 91 and extending alongside the reservoir 90 is a liquid level indicating device or sight tube 95 by which the level of the lubricant within the reservoir 90 is determined.

Assuming that the reservoir 90 requires filling, the valves 88 and 89 are both closed and the closure member 94 is removed, whereupon the reservoir is completely filled with lubricant and the closure member 94 replaced to prevent the ingress of air to the reservoir 90 when lubricant is removed therefrom.

When it becomes necessary to introduce lubricant into the sump, the vent valve 88 is opened to permit a transfer or equalization of air pressures above the lubricant in the arbor housing 38 through the vent conduit 85 and to the top of the reservoir 90. The valve 89 is now opened and hydrostatic force causes lubricant to flow through the supply conduit 86 into the sump. When the necessary quantity of lubricant has been admitted to the sump, as determined by the sight tube 87, the valve 89 is closed. It is necessary to isolate completely the supply mechanism from the arbor housing only while the reservoir 90 is being filled. Otherwise it is sufficient to close supply valve 89 in the conduit 86 to isolate the lubricant in the reservoir from the sump. Lubricant may be drained from the system by removing drain plug 96.

It is to be noted that the valves 88 and 89 do not isolate the sight gauge 87 from the sump nor do they isolate the sight gauge 95 from the reservoir 90; but they do function to isolate both the reservoir 90 and sight gauge 95 as a unit or assembly from the sump to permit filling of the reservoir. Thus, the gauges 87 and 95 function to indicate accurately the level of the lubricant in the respective compartments to which they are connected.

I have described the operation of the lubricant supply apparatus 23 while being used to introduce lubricant into the arbor housing or sump while the ventilator is in operation, but it will be seen that the apparatus is usable for filling or replenishing the lubricant in the sump when the ventilator is not in operation. However, as previously described, the filler mechanism 23 is most used when the ventilator is in operation because it is undesirable to stop the operation of the ventilator.

Referring now to Fig. 7, a ventilator is shown that includes another embodiment of my inven-

tion. The arbor or spindle of this ventilator is belt driven; the belts extending from a pulley mounted on the arbor or spindle shaft through a suitable housing 100 into the motor shed 117 and about a pulley on the motor shaft. In this embodiment the lubricant introducing apparatus 23 is employed for determining and maintaining the level of the lubricant within the arbor or spindle housing.

The arbor or spindle of this embodiment of my invention is shown in detail in Fig. 8 and includes the housing 38 from which the pinion and its associated shaft parts are omitted, the boss 66 being closed by a suitable cap, not shown. Extending through the housing 38 and bearinged therein by means identical to that shown in the arbor or spindle of Figs. 2 and 4 is an arbor or spindle shaft 144 that extends outwardly through the disc-like plate 60 and carries a pulley 101. The end of this portion of the shaft 144 is supported by an open type anti-friction bearing 102 that is mounted in a bearing housing 103 supported on a stand 114 anchored to the concrete base 128 of the ventilator. The bearing housing 103 includes an end cover or cap 104 that completely encloses one side of the bearing 102 and the end of the shaft 144 and forms a pocket or distributor 105 for directing lubricant into the bearing 102.

The inner side of bearing housing 103 carries a cover member 106 that surrounds the shaft 144 and is provided with a lubricant seal 107 that seals it with the shaft 144. The cover member 106 forms a pocket 108 into which lubricant flows after it passes through bearing 102 and from where it is returned to the sump in the arbor or spindle housing 38 through a suitable conduit 109.

In this embodiment of my invention the lubrication system for the bearings in the arbor or spindle housing 38 is also identical to that described in connection with the embodiment shown in Figs. 2 and 4, except that the gear 46 is substituted by a slinger or splasher wheel 110 that functions to raise, elevate or throw lubricant from the sump into the troughs 69 and 70. The lubricant is spilled from the troughs into the wells 71 and 72. Connected into the well 72 in disc-like plate 60 is a conduit or passageway 111 that conveys lubricant therefrom into the pocket or distributor 105 formed by cap 104 of the bearing housing 103. Preferably the conduits 109 and 111 include unions 112, and conduit 109 includes a valve 113 for isolating the bearing housing from the sump.

When it becomes necessary to replace any or all of the belts that connect the motor and arbor, valve 113 may be closed and the housing 103 may be removed from bearing 102 by removing the cover member 106. New belts may be placed on the pulley 101 by disconnecting the unions 112 to split conduits 109 and 111. In this embodiment of my invention the cap 62 on the disc-like plate 60 is replaced by a cover member identical to cover member 106.

In operation, in this embodiment lubricant flows from the well 72 into the cover plate 60 to both the bearings 49 and 102 and is returned therefrom to the sump to be recirculated.

From the foregoing description of my invention it will be seen that my invention provides an efficient mechanism whereby lubricant may be introduced into a chamber upon which other forces function to reduce or increase the gas pressure therein substantially without affecting said pressure and that such has enabled me to provide a ventilator in which the lubricant level

in the arbor or spindle may be determined and maintained from outside the ventilator housing and preferably from within the motor shed. It will also be seen that I have provided an improved fan or impeller spindle or arbor wherein the ventilator rotor is carried by shaft 44 that is mounted by spaced anti-friction bearing means 40 and 49 which are enclosed within the housing 38 and are lubricated by lubricant contained within a sump in the housing, which lubricant is circulated by a lubrication system wherein lubricant is lifted, thrown or slung from the sump to an elevated position from whence it flows by reason of hydrostatic force through the shaft bearings and is returned to the sump of the housing to be recirculated. Furthermore, the bearing assembly 40 constitutes a thrust bearing to take the axial load developed by the rotor 34 in operation. As a consequence of my structure only two bearing assemblies are required for supporting the rotor.

In the embodiment disclosed, particularly in Figs. 1 and 2 of the drawings, the rotor is driven from a motor 18 contained within motor shed 17 which is located entirely outside the fan casting or housing 10. As a consequence of this fact, the drive shaft 21 extends through the air stream since it extends through the outer fan casing or housing 10 and the centrally located fairing 15. It is to be noted, however, that the drive shaft 21 is not exposed directly to the stream of flowing air, but is housed by drive shaft housing 19 which with the fairing 15 provides a generally streamline construction.

Furthermore, it is also to be noted that the lubricating mechanism by which lubricating oil in the arbor housing 38 is replenished is by virtue of the lubricating apparatus 23 which is also located entirely outside the air stream and within the motor shed 17. As a consequence of this fact the pressure equalizing and lubricating supply conduits 85 and 86 also extend through the air stream since they extend between the ventilator housing 11 and the fairing 15.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

- 55 1. A completely enclosed drive mechanism particularly adapted for use in a ventilator including in combination a structural housing adapted to support a fan and forming a sump for lubricant, spaced aligned anti-friction bearings in said housing positioned above the level of said sump, a fan shaft extending through said housing and carried by said bearings, sealing means disposed between said shaft and housing, a gear drivingly mounted on said shaft extending into said sump and functioning as a lubricant slinger, a drive shaft extending through a side wall of said housing, anti-friction bearing means supporting said drive shaft, a gear mounted on the inner end of said drive shaft driving said first named gear and fan shaft, a lubricant well formed by said housing above each of said fan shaft bearings, trough means in said housing adapted to catch lubricant thrown from said sump by said first named gear and convey said lubricant to said wells, and passages leading from said wells to said bearings whereby lubricant flows from said

wells to said bearings and back to said sump by reason of gravity.

2. A completely enclosed drive mechanism particularly adapted for use in a ventilator including in combination a structural housing adapted to support a fan and forming a sump for lubricant, spaced aligned anti-friction bearings in said housing positioned above the level of said sump, a fan shaft extending through said housing and carried by said bearings, a gear drivingly mounted on said shaft extending into said sump and functioning as a lubricant slinger, a drive shaft extending through a side wall of said housing, anti-friction bearing means supporting said drive shaft, a gear mounted on the inner end of said drive shaft driving said first named gear and fan shaft, a lubricant well in said housing above each of said fan shaft bearings, trough means in said housing adapted to catch lubricant thrown from said sump by said first named gear and convey said lubricant to said wells, and passages leading from said wells to said bearings whereby lubricant flows from said wells to said bearings and back to said sump by reason of gravity.

3. In a fan spindle assembly, a stationary housing forming a sump for lubricant, a shaft extending through said housing adapted to carry a fan, sealing means disposed between said shaft and housing preventing the escape of lubricant from said housing, spaced open type anti-friction bearings supporting said shaft positioned above the level of said sump, means functioning as a lubricant slinger disposed in said housing mounted for rotation with said shaft and extending into said sump, lubricant wells formed by said housing above the level of said bearings, means adjacent a side of each of said open anti-friction bearings forming pockets directing lubricant into said open anti-friction bearings, conduit means interconnecting said wells and pockets, and trough means in said housing adapted to catch lubricant slung from said sump by said slinger means and convey said lubricant to said wells whereby said lubricant is lifted from said sump and caused to flow by gravity through said trough means, wells, conduits, and pockets through said open anti-friction bearings and return to the sump by reason of gravity.

4. In a fan spindle assembly, a stationary housing forming a sump for lubricant, a shaft extending through said housing adapted to carry a fan, spaced open type anti-friction bearings supporting said shaft positioned above the level of said sump, means functioning as a lubricant slinger disposed in said housing mounted for rotation with said shaft and extending into said sump, lubricant wells formed by said housing above the level of said bearings disposed to receive lubricant slung from said sump by said slinger means, means adjacent a side of each of said open anti-friction bearings forming pockets directing lubricant into said open anti-friction bearings, and conduit means interconnecting said wells and pockets whereby said lubricant is lifted from said sump and caused to flow by gravity through said wells, conduits, and pockets through said open anti-friction bearings and return to the sump by reason of gravity.

5. A fan spindle assembly including a stationary housing forming a sump for lubricant, a shaft in said housing extending through an end wall thereof and adapted to carry a fan on its extending end, sealing means disposed between said shaft and housing preventing the escape of lubricant from said housing, spaced open type anti-

friction bearings supporting said shaft positioned above the level of said sump and within said housing, gear means drivingly mounted on said shaft extending into said sump and functioning as a lubricant slinger, lubricant wells formed by said housing above the level of said bearings, means adjacent a side of each of said bearings forming pockets for directing lubricant into a side of each of said open anti-friction bearings, conduit means interconnecting said wells and pockets, trough means in said housing adapted to catch lubricant slung from said sump by said gear and convey said lubricant to said wells, and a power driven pinion gear in said housing driving said first named gear whereby said lubricant is lifted from said sump and caused to flow by gravity through said trough means, wells, conduits, pockets, and through said open bearings and return to the sump by reason of gravity.

6. A fan spindle assembly including a stationary housing forming a sump for lubricant, a shaft in said housing extending through an end wall thereof and adapted to carry a fan on its extending end, sealing means disposed between said shaft and housing preventing the escape of lubricant from said housing, spaced open type anti-friction bearings supporting said shaft positioned above the level of said sump and within said housing, gear means drivingly mounted on said shaft extending into said sump and functioning as a lubricant slinger, lubricant wells formed by said housing above the level of said bearings disposed to receive lubricant slung from said sump by said gear, means adjacent a side of each of said bearings forming pockets for directing lubricant into a side of each of said open anti-friction bearings, conduit means interconnecting said wells and pockets, and a power driven pinion gear in said housing driving said first named gear whereby said lubricant is lifted from said sump and caused to flow by gravity through said wells, conduits, pockets, and through said open bearings and return to the sump by reason of gravity.

7. A fan spindle assembly including a stationary housing forming a sump for lubricant, a shaft in said housing extending through an end wall thereof and adapted to carry a fan on its extending end, sealing means disposed between said shaft and housing preventing the escape of lubricant from said housing, spaced open type anti-friction bearings supporting said shaft positioned above the level of said sump and within said housing, gear means drivingly mounted on said shaft extending into said sump and functioning as a lubricant slinger, lubricant wells in said housing above the level of said bearings, means adjacent a side of each of said bearings forming pockets for directing lubricant into a side of each of said open anti-friction bearings, conduit means interconnecting said wells and pockets, trough means in said housing adapted to catch lubricant slung from said sump by said gear and convey said lubricant to said wells, and a power driven pinion gear in said housing driving said first named gear whereby said lubricant is lifted from said sump and caused to flow by gravity through said trough means, wells, conduits, pockets, and through said open bearings and return to the sump by reason of gravity.

8. In a fan spindle assembly a stationary housing forming a sump for lubricant, a shaft extending through said housing adapted to carry a fan, spaced open type anti-friction bearings in said housing supporting said shaft and positioned above the level of said sump, a lubricant slinger disposed in said housing mounted for rotation

with said shaft and extending into said sump, lubricant wells formed by said housing above the level of said bearings disposed to receive lubricant slung by said slinger, means adjacent a side of each of said bearings forming a pocket directing lubricant into said bearing, conduit means connecting said wells and pockets, a second stationary housing spaced from said first housing, an open type anti-friction bearing in said second housing carrying an end of said shaft, a pulley on said shaft disposed between said housings, means adjacent a side of said bearing forming a pocket directing lubricant into said bearing, conduit means connecting said pocket with one of said wells, and conduit means connecting said last named housing with said sump whereby lubricant is lifted from said sump and caused to flow by gravity through said wells, conduits and pockets through said bearings and return to said sump by gravity.

9. In a fan arbor assembly a stationary housing forming a sump for lubricant, a shaft extending into said housing adapted to carry a fan, an open type anti-friction bearing in said housing supporting said shaft and positioned above the level of said sump, a lubricant slinger disposed in said housing mounted for rotation with said shaft and extending into said sump, a lubricant well in said housing above the level of said bearing disposed to receive lubricant slung by said slinger, means adjacent a side of said bearing forming a pocket directing lubricant into said

bearing, a passageway for lubricant connecting said well and pocket, a second stationary housing spaced from said first housing, an open type anti-friction bearing in said housing carrying said shaft, a pulley on said shaft disposed between said housings, means adjacent a side of said bearing forming a pocket directing lubricant into said bearing, conduit means connecting said pocket with said well, and conduit means connecting said last named housing with said sump whereby lubricant is lifted from said sump and caused to flow by gravity through said well, conduits, and pockets through said bearings and return to said sump by gravity.

15

bearing, a passageway for lubricant connecting said well and pocket, a second stationary housing spaced from said first housing, an open type anti-friction bearing in said housing carrying said shaft, a pulley on said shaft disposed between said housings, means adjacent a side of said bearing forming a pocket directing lubricant into said bearing, conduit means connecting said pocket with said well, and conduit means connecting said last named housing with said sump whereby lubricant is lifted from said sump and caused to flow by gravity through said well, conduits, and pockets through said bearings and return to said sump by gravity.
